DESIGN FOR A CHILD'S SWEATER

Abraham Kaplan, Jamaica, N. Y., assignor to Avonshire Knitwear, Inc., New York, N. Y., and Monitor Knitwear Corp., New York, N. Y.

Application March 15, 1947, Serial No. 137,640

Term of patent 3½ years

(Cl. D3—4)

To all whom it may concern:

Be it known that I, Abraham Kaplan, a citizen of the United States, residing at 186—14 Avon Road, Jamaica, Long Island, New York, county of Queens, and State of New York, have invented a new, original, and ornamental Design for a Child's Sweater, of which the following is a specification, reference being had to the accompanying drawing, forming a part thereof.

The figure on the drawing is a rear view of a child's sweater showing my new design.

The front of the sweater is similar in appearance to the rear view disclosed.

I claim:

The ornamental design for a child's sweater, as shown and described.

ABRAHAM KAPLAN.
